“Electric Vehicle Charging Stations”, posted by Jay Graham on Oct. 26, 2020 on powerplant.com.au. URL: <<https://powerplant.com.au/2020/10/26/electric-vehicle-charging-stations/>>. (Year: 2020).*

Primary Examiner — Rosemary K Tarcza

(74) Attorney, Agent, or Firm — LUCAS & MERCANTI, LLP

(57) **CLAIM**

The ornamental design for charging station for electric vehicles, as shown and described.

DESCRIPTION

FIG. 1 is a front left perspective view of a first embodiment of charging station for electric vehicles according to the design;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof;

FIG. 8 is a front left perspective view of a second embodiment according to the design;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the drawings depict portions of the charging station that form no part of the claimed design.

1 Claim, 10 Drawing Sheets
